UNITED STATES PATENT OFFICE.

AVIE JOHN LUMAN, OF BERKELEY, CALIFORNIA.

DOOR BOLT.

Application filed February 24, 1925. Serial No. 11,253.

To all whom it may concern:

Be it known that I, AVIE JOHN LUMAN, a citizen of the United States, and a resident of Berkeley, in the county of Alameda and 5 State of California, have invented a new and useful Improvement in Door Bolts, of which the following is a specification.

The present invention relates to improvements in door bolts and has particular 10 reference to detachable means for locking a door against opening which is of particular advantage to travellers who desire an easily attachable and detachable means for locking the door leading to their room 15 against intruders.

My invention is particularly designed to be used for a door opening inwardly and 20 comprises in its principal features a guideway that may be quickly attached to the casing of the door and has a bolt retractible therein which may be projected and is provided with means for turning the same at 25 right angles to the guideway into abutting relation with the door when projected.

Further objects and advantages of my 30 device will appear as the specification proceeds.

The preferred form of my invention is 35 illustrated in the accompanying drawing, in which—

Figure 1 shows my locking means in place, the door and the door frame being shown in section.

Figure 2 a plan view of my locking means 40 detached from the door casing.

Figure 3 a section taken along line III—III of Figure 2, and

Figures 4 and 5 longitudinal sections taken 45 along line IV—IV of Figure 2, Figure 4 showing the bolt retracted and Figure 5 showing the bolt in locking position.

While I have shown only the preferred 50 form of the invention, it should be understood that various changes or modifications 55 may be made within the scope of the claims hereto attached with departing from the spirit of the invention.

In Figure 1 is shown the usual door 55 arrangement including upright studdings 1 which serve as a support for furring strips 2 nailed to the sides thereof and for the plaster 3 which may be secured thereto in any suitable manner well known in the art as by laths, not shown in the drawing. The 60 end face of the studdings 1 and the furring strips is covered by the door jamb 4 and

strips of finished lumber 6, known in the trade as casings, are nailed to the furring strips to finish the frame of the door opening. A stop 7 may be nailed to the inner 60 face of the jamb for the door 8 to lie against when the door is closed, the outer face 9 of the door being usually flush with the edge 11 of the door jamb so that the casing 6 projects beyond the plane of the closed 65 door.

My locking means comprises a guideway 12 consisting preferably of a sheet of metal bent into rectangular form with the end edges 13 disposed in confronting relation. 70 This guideway has flanges 14 extending from one end of the base thereof, the flanges being preferably coextensive with the thickness of the casing 6 so that they may lie against the inner edge of the casing while 75 teeth 16 project from the flanges inwardly and may be driven into the crack between the casing and the door jamb 4. The other end of the guideway has a lip 17 extending therefrom which is perforated as shown at 80 18 and may be fastened to the casing by means of a screw 19 after the teeth have been driven into place. The guideway has an element 21 slidable therein, this element 85 preferably consisting of a channel including a web 22 and the two flanges 23 and being dimensioned for sliding engagement with the guideway with the handle 24 extending through a slot 26 in the top of the guideway so that the element 21 may be slid back 90 and forth in the guideway by means of the handle.

The bolt 27 may also be made of a channel shaped piece of metal corresponding in form substantially to the element 21 and has its 95 inner end pivoted to the channel by means of a pin 28 at a line remote from the base of the guideway and from the casing. The inner corner 31 of each flange 32 of the bolt is preferably rounded off so as not to 100 interfere with the operation described hereinafter. The inner end of the web 33 of the bolt is turned inwardly as shown at 34 and is connected by means of a spring 36 to the rear end 37 of the guideway in such a 105 manner that the line along which the spring pulls is closer to the base of the guideway or to the casing than the pin 28. The front face 38 of the bolt is preferably provided 110 with a cushion member 39.

The manner of using my locking means is as follows:

The base of the guideway is placed against the exposed face of the casing with the flanges 14 facing the edge of the casing and the teeth 16 are driven into the crack between the casing and the jamb so as to bring the flange 14 into contact with the edge of the casing, whereupon the screw 19 is inserted through the perforation 18 in the lip 17 and threaded into the wood of the casing so that the guideway is firmly held against removal. To lock the door, it is only necessary to push the handle 24 to the left which causes the bolt to project outwardly and to turn on the pin 28 due to the action of the spring 36 which brings the end face 39 of the bolt into abutting relation with the face of the door and prevents the latter from being opened. To unlock the door, the handle 24 is pushed backwardly whereupon the pin 28 automatically retracts the bolt into the guideway, the spring 36 yielding sufficiently to allow the bolt to be brought into alignment with the element 21 while the curved edge 31 rides on the corner of the guideway for bringing the bolt into alignment with the element 21. To detach the locking means, the screw 19 is threaded out of the wood and a slight push on the guideway to the left, as viewed in Figure 1, disengages the teeth 16 from the casing.

I claim:

1. Locking means for a door having a casing framing the same and projecting beyond the plane of the closed door, comprising a guideway fixed to the casing adjacent the free end of the door and a bolt retractable therein having means associated therewith for turning the same around the edge of the casing into abutting relation with the face of the door when the bolt is projected.

2. Locking means for a door having a casing framing the same and projecting beyond the plane of the closed door, comprising a guideway fixed to the casing adjacent the free end of the door, a bolt slidable therein and spring means for retracting the same, the latter means being arranged to turn the bolt around the edge of the casing into abutting relation with the face of the door when the bolt is projected.

3. Locking means for a door having a casing framing the same and projecting beyond the plane of the closed door, comprising

ing a guideway fixed to the casing adjacent the free end of the door, an element slidable therein having operating means extending through the wall of the guideway, a bolt pivoted to the element along a line remote from the casing and elastic means tending to retract the bolt engaging the same in proximity to the casing so as to cause the bolt to turn around the edge of the casing into abutting relation to the face of the door when the said element is projected.

4. Locking means for a door having a casing framing the same and projecting beyond the plane of the closed door, comprising a guideway adapted to lie against the outer face of the casing having a flange extending from one end thereof adapted for contacting engagement with the edge of the casing, with teeth projecting from the end of the flange adapted to be driven into the casing material and means associated with the other end of the casing for preventing disengagement of the teeth, and means slidable in the guideway adapted to be brought into abutting relation with the face of the door for preventing the opening of the same.

5. Locking means for a door having a casing framing the same and projecting beyond the plane of the closed door, comprising a guideway adapted to lie against the outer face of the casing having a flange extending from one end thereof adapted for contacting engagement with the edge of the casing, with teeth projecting from the end of the flange adapted to be driven into the casing material, and a lip extending from the other end of the guideway adapted for fastening to the casing for preventing disengagement of the teeth from the latter and means slidable in the guideway adapted to be brought into abutting relation with the face of the door for preventing the opening of the same.

6. In a device of the character described, a guideway, a bolt slidable therein and means associated therewith for turning the bolt at right angles to the guideway when the bolt is projected, comprising an element slidable in the guideway having the bolt hinged thereto at a line remote from the base of the guideway and elastic means tending to retract the bolt engaging the same near the base of the guideway.

AVIE JOHN LUMAN.
